UNITED STATES PATENT OFFICE.

ODO BUZZICKA AND WILLIAM L. BRUMFIELD, OF NEWARK, NEW JERSEY, ASSIGNEES
OF ONE-FIFTH TO GEORGE POLANER, ONE-FIFTH TO MILTON GUTTMAN, AND ONE-
FIFTH TO JOHN S. GUTTMAN, ALL OF NEWARK, NEW JERSEY.

STEM FOR PIPES.

Application filed March 15, 1926. Serial No. 94,647.

This invention relates to an improved pipe and is designed to provide a pipe of that type that has a stem with a laterally removable inlay so that the stem can be easily 5 cleaned.

We are aware that stems have been made with removable or separable sections but in the present device we provide a stem that is held so that the inlay does not tilt or become 10 displaced solely by its engagement with the stem extension of the bowl. This not only reduces the number of parts to three, two sections of the stem and the bowl, but it also provides for a cheaper pipe.

15 The invention is illustrated in the accompanying drawing in which Figure 1 is a section of the pipe bowl and its stem extension, the stem proper being shown in elevation. Figure 2 is an enlarged section taken on line 20 2-2 in Figure 1. Figure 3 is a perspective view of the two parts of the pipe stem separated and Figure 4 is a section showing the stem as applied to a cigar holder.

We show a conventional form of pipe 25 bowl 10 which has the receptacle 11 for the tobacco and a stem extension 12. Stem 13 fits in the bore 14 of the stem extension and is made of two pieces or sections that can be separated laterally, these sections consisting 30 of the member 15 which is the main member and an inlay 16 which is adapted to fit tightly in the groove 17 of the member 15. The fit is a tight one so that the member 16 must be pressed, by the fingers of the hand, snugly 35 into the slot 17, the abutting parts being constructed so that the bore 18 is formed when the inlay 16 is pressed in as far as it will go, the entrance usually being limited by the sides 19 of the slot 17 converging. 40 The main member 15 is thus provided with a slot which has side walls that tightly grasp the inlay 16 and this friction is strong enough to make longitudinal movement extremely difficult but lateral movement is 45 easy. The slot is no wider than the bore and the two members have co-acting means to cause the bottom part of the slot to act as a stop for the inward movement of the inlay and still leave enough clearance to form 50 the bore 18. The two parts of the stem when thus assembled are slid into the recess 14 in the stem extension 12, this being a tight, or what might be termed a snug fit and it will, furthermore, be noted that the

bore 14 extends to a point beneath the opening 20 in the bottom of the receptacle 11 of the bowl. This gives a bearing or contact of considerable length and the stem extension or rather the bowl forms the sole means for holding the two members 15 and 16 of the stem together other than by their frictional contact.

The stem when it is to be cleaned is pulled 55 out of the bowl and the members 15 and 16 are separated and it will be evident from Figure 3 that the slot 17 and the underface of the inlay 16 can be cleaned by wiping. Since the parts were made to fit snugly, the members 15 and 16 are made so that they 60 can be easily separated. This is done by extending the member 16 so that its end 21 extends beyond the end of the member 15 as will be seen from Figure 1, this extension being possible because the passage 20 allows such space to be utilized. This part 21 thus 65 forms a finger piece or projection by means of which the inlay 16 can be pulled laterally 70 out of the slot 17.

When the parts are to be assembled after 75 cleaning all that need be done is to push the inlay laterally into the slot 17 and then slide the members so assembled into the recess 14 of the bowl. It will be noted that the recess 14 is, therefore, relatively large and enables 80 the passage 20 to be kept clean without difficulty.

In Figure 4 we show a device adapted for 85 a cigar holder, the holder portion 22 being used in this case as the equivalent of the bowl 10 in the pipe.

We claim:

1. A pipe comprising a bowl with a stem extension, a stem fitting into the extension to a point under the receptacle of the bowl and extending therefrom to form a mouthpiece, the stem having an inlay extending from end to end of the stem, and insertible laterally into a groove in the stem and being limited as to its inward movement by the bottom of the groove and thus form the bore. 90

2. A pipe stem comprising a body portion with a groove from end to end, a laterally insertible inlay fitting in the groove and completing the stem when in place, the inlay projecting at the inner end of the stem slightly 95 beyond the body portion.

3. A pipe stem comprising a body portion with a longitudinal groove and an inlay fit-

ting in the groove and removable and insertible laterally, and held in place by the friction between the walls of the groove and the sides of the inlay.

5. 4. A pipe stem comprising a body portion with a slot extending from the centre to the outer edge of the said portion and of substantially the same width throughout and an inlay fitting snugly in the slot and held therein solely by the friction between the parts, said inlay being insertible and removable laterally.
10. 5. A pipe stem comprising a body portion

with a slot extending from the centre to the outer edge of the said portion and of substantially the same width throughout and an inlay fitting snugly in the slot and held therein solely by the friction between the parts, said inlay being insertible and removable laterally, the bottom of the slot converging to act as a stop to limit the inward movement of the inlay to form the bore.

In testimony whereof we affix our signatures.

ODO RUZSICSKA.
WILLIAM L. BRUMFIELD.
